TELETYPEWRITER SWITCHING SYSTEM

Russell Jacob Anspach, Westfield, N. J., assignor
to American Telephone and Telegraph Company, a corporation of New York

Application September 6, 1941, Serial No. 409,768

7 Claims. (Cl. 178—2)

This invention relates to telegraph and teletypewriter systems and more particularly to round robin systems for telegraph or teletypewriter circuits and apparatus.

There are at present several types of so-called "round robin systems" in use in which a plurality of teletypewriter stations are interconnected in the form of a ring or loop in such a way that messages may be transmitted from any one of the stations in the system to all of the other stations so that all of the stations, including the station transmitting the messages, may receive the messages and prepare copies of the messages. In the usual round robin system two paths are provided to connect each station into the round robin system, one of the paths being employed for transmitting from the station into the rest of the round robin system and the other path for receiving messages from the other stations. Local copy is obtained after transmission of the messages around the ring or loop of the system. In many cases some stations may be in locations where line facilities are limited, and considerable construction might be required to provide separate sending and receiving legs to such stations to include such stations in the round robin systems. In such cases it would be advantageous to operate these legs in such a manner that sending and receiving operations, together with cutting and uncutting operations to connect or disconnect the remote stations into the round robin system, could be done over a single line conductor instead of over two conductors as has been the prior practice.

In accordance with this invention there is provided a novel form of round robin system for teletypewriter or like apparatus, the round robin system including one or more outlying points at which teletypewriter apparatus may be located. In the arrangement to be described hereinafter the outlying point to be specifically considered may be connected by a single telegraph channel to the central office which is connected to the round robin system. Arrangements are provided for permitting the operator at the outlying point to "cut" his teletypewriter apparatus into or out of the round robin system as desired, and at the same time allow the operator at the outlying point to obtain a copy of his own messages. Thus in the arrangement contemplated the apparatus at the outlying point will receive a copy of all messages transmitted over the round robin system in the usual manner, but after a "cut" is instituted at the outlying point, the operator at the outlying point may send mes-

sages into the round robin system and home copy of the messages emanating from the outlying point will be received over a local circuit.

This invention will be better understood from the detailed description hereinafter following when read in connection with the accompanying drawing showing one embodiment of the invention merely for the purpose of illustration.

Referring to the drawing, there is shown a round robin system for teletypewriter apparatus, the system interconnecting a plurality of stations designated STA₁, STA₂ and STA₃ and another station which may include a central office CO and an outlying station or point OP which is connected to the central office by a single line conductor E. As is well known, messages emanating from any one of the stations, such as STA₁, will be transmitted to all of the other stations including the central office CO and its connecting station OP, so that copies of the messages may be prepared at each of the various stations and at the outlying point OP. The outlying point OP may include a break relay A, a receiving relay B, the armature of which is connected to a teletypewriter TTY, a sending relay S and a key L for cutting the sending apparatus at the outlying point into or out of the round robin system, as will be described more fully hereinafter. The apparatus at the central office CO may include a relay V, one of the windings V₁ of which is always connected to the round robin system; a relay P which is normally unoperated but becomes operated only when the key L at the outlying point OP is manipulated to "cut" the sending apparatus of the outlying point OP into the round robin system, the relay P being released when the key L is returned to its "uncut" position; a relay W having its main winding W₁ in series with the line E which extends between the outlying point OP and the central office CO, as well as other relays to be subsequently described.

When messages are transmitted over the round robin system from any one of the stations STA₁, STA₂ or STA₃, the currents flowing through the winding V₁ of the relay V will move its armature between its contacts M and S to connect oppositely poled batteries to the line E over a circuit which includes the armature of relay V, the armature P₇ of relay P and its back contact, the noise killer and potentiometer N₁, the break-after-make contact of armature P₅ of relay P, the winding W₁ of relay W and the resistor Z₁. The line E is connected to ground at the contact of swinger L₁ of the key L at the outlying point OP,

the interconnected circuit including the lower swinger L_2 and contact of the key L and the winding B_1 of relay B . Oppositely directed currents corresponding to the oppositely poled voltages supplied to the contacts of the armature of relay V will traverse the winding B_1 of relay B and the armature of relay B will be moved between its marking and spacing contacts M and S to operate the teletypewriter TTY in accordance with the received signals. Thus the teletypewriter TTY will prepare a record of all messages passed over the round robin system.

When the operator at the outlying point OP desires to interrupt the transmission from the other stations so that he may transmit messages over the round robin system, he will operate the key L by moving it to the left. The upper swinger L_1 of the key L will then be disconnected from ground and instead connected to positive battery over a circuit which includes another noise killer and potentiometer N_2 and the armature and contact M of the relay S . At the same time the short-circuit around the winding A_1 of relay A will be opened at the lower swinger L_2 of the key L . Thus the line E will be connected at the outlying point OP to the positive battery. At the central office CO the line E will be connected to negative battery connected to the marking contact M of the relay V . The increased current over the line E which follows the operation of the key L will cause the armature of the relay A to move to its spacing contact S . This in turn will cause the negative battery connected to the spacing contact S of relay A to be connected through a resistor Z_2 to the lower winding B_2 of relay B , and hence the armature of relay B will move to its spacing contact S . When this happens, the teletypewriter TTY will be open-circuited at the contact S of relay B , and the teletypewriter will, therefore, run "open."

The increased current over line E which results from the operation of the cutting key L also causes relay W at the central office CO to operate so as to move its armature to its marking contact M . Relay P will then operate, current flowing from positive battery connected to resistor Z_4 , through the winding of relay P , the break-after-make contact of armature P_2 of relay P , the armature and contact M of relay W and the negative battery connected thereto. Immediately after relay P operates, it becomes locked in its operated condition over a circuit which includes positive battery, resistor Z_4 , the winding of relay P , the armature P_2 of relay P and its make-before-break contact, the break-after-make contact of relay D_2 and the negative battery connected to the make-before-break contact of relay D_1 . Thus the relay P becomes operated immediately after key L is closed and becomes locked immediately thereafter.

The operation of relay P grounds the line E at the central office CO over a circuit which includes resistor Z_1 , the winding W_1 of relay W , the make-before-break contact of armature P_5 of relay P , armature P_5 , and the armature and back contact of relay Q . The operation of relay P at the same time opens the circuit of the biasing winding W_2 of relay W at the back contact of armature P_6 of relay P , this winding having formerly been connected to positive battery by way of resistor Z_6 and the back contact and armature P_6 of relay P . Moreover, the round robin system will be split at the break-after-make contacts of armatures P_0 and P_1 of relay P to allow signaling currents to be transmitted from sta-

tion OP to the round robin system, as will be described. The armature of relay W will be connected to the sending side of the round robin system over a circuit which includes the marking contact M and armature of relay W , the armature and contact M of relay Y , the resistor Z_8 , the armature P_0 of relay P and its make-before-break contact. This permits the pulses transmitted to relay W from station OP over line

10 E to be repeated into the round robin system, so that the signals corresponding to these pulses may be reproduced at the stations STA_1 , STA_2 and STA_3 .

The operation of relay P also causes the armature of the relay V to be connected to the slow-release relay D_2 over a circuit which includes the armature P_4 of relay P and its make contact, the make contact and armature P_3 of relay P , the winding of relay D_2 , the resistor Z_{10} and positive battery. This will enable any break signal received from any one of the stations STA_1 , STA_2 or STA_3 to cause the armature of relay V to close its spacing contact S and hence allow positive battery to be connected to opposite terminals of the winding of the slow-release relay D_2 , so that in due course the relay D_2 will be released. The release of relay D_2 will result in "opening" the circuit of the teletypewriter at TTY station OP to apprise the operator of the break 30 signal, as will be subsequently described.

The now normal line current traversing line E causes the relay A at the outlying point OP to return to its marking contact M . This removes current from the bias winding B_2 of relay B , 35 thereby permitting relay B to return its armature to its marking contact M . When the marking contact M of relay B is closed, the teletypewriter TTY is then connected over a completed circuit through the armature of relay B and 40 its marking contact M and, therefore, the teletypewriter TTY will stop running "open," thereby indicating that the "cut" has been fully effected.

After the "cut" has been completed, the operator at the outlying point OP may then send signals over the round robin circuit, as will now be described. To transmit such signals the key K , which is in series with the W_1 winding of relay S and a battery, may be operated. When the 45 key K is closed, the current in the W_1 winding of relay S will overpower the biasing current in winding W_2 and the armature of relay S will be moved to its marking contact M , thereby applying positive battery to the line E over a circuit 50 which includes the apparatus N_2 , the back contact and armature L_1 of key L , the winding B_1 of relay B and the winding A_1 of relay A . The opening of key K will, on the other hand, cause the current in winding W_1 to fall to zero and 55 the armature of relay S will be positioned on its spacing contact S by the biasing current in winding W_2 , thereby connecting negative battery to the line E over the same circuit as already described. Thus the operation of key K will be

60 employed to apply oppositely poled batteries to the line E to transmit one-way polar signals in the usual way over the line E to the central office CO , a positive battery being connected to line E for the marking condition and a negative battery for the spacing condition. These oppositely poled batteries will move the armature of relay W between its marking and spacing contacts M and S , and oppositely poled batteries will be connected to the sending side of the round robin system over a circuit controlled by the armature 70 75

of relay W as already described. These oppositely poled batteries will convey the transmitted signals to the various stations of the round robin system in a well-known manner.

The operator at the outlying point OP may uncut his transmitting circuit from the line E by releasing the key L. This may be done by moving the key L to the right. This then grounds the line E at the swinger L₁ of key L, and at the same time returns the short circuit around the winding A₁ of relay A, which is completed by the lower swinger L₂ of key L. Thus the line E now becomes grounded at both ends and, therefore, no current flows thereover. The absence of voltage across the resistor Z₁ which is in series with the line E removes current from the full wave rectifier R bridging the resistor Z₁, and hence no current flows through the upper windings of relays X and Y. The armatures of relays X and Y, therefore, move to their spacing contacts S. The closure of contact S of relay X by its armature results in the removal of current from the slow-release relay D₁ and relay D₁ releases. The release of relay D₁ opens the locking circuit for relay P, the locking circuit, as already explained, including the negative battery connected to the break-after-make contact of relay D₁, the break-after-make contact of relay D₂, the armature P₂ and its make-before-break contact of relay P, the winding of relay P, resistor Z₄ and positive battery. Relay P consequently releases. The armatures P₀ and P₁ of relay P become restored to their former positions as shown in the drawing and the round robin system is then returned to its original condition. Relay P is so constructed that, in releasing, the armature and contact P₆ of relay P will close before armature P₂ makes with its normal contact. This insures that the armature of relay W will be on its S contact thus preventing the reoperation of relay P as would happen if relay W were on its M contact when the P₂ armature of relay P made with its normal contact.

As already pointed out, a break signal received over the round robin system while the circuit at the outlying point OP is "cut" into the round robin system, causes the relay D₂ to release. The release of relay D₂ opens the shunt around the winding of relay Q previously established by the break-after-make contacts of relay D₂. The removal of this shunt from the winding of relay Q permits relay Q to operate, the operating circuit for relay Q including the negative battery connected to the break-after-make contact of relay D, the winding of relay Q, the armature P₂ of relay P and its make-before-break contact, the winding of relay P, the resistor Z₄ and the positive battery connected thereto. The operation of relay Q connects negative battery to the line E over a circuit which includes the negative battery connected to the make contact of the armature of relay Q, the armature P₅ of relay P and its make-before-break contact, the winding W₁ of relay W and resistor Z₁. Due to the connection of oppositely poled batteries to the opposite terminals of line E whenever the armature of relay S closes its marking contact M, the increased line current will operate relay A, which will move its armature to its spacing contact S. This will then cause relay B to operate its armature to its spacing contact S, and the circuit to the teletypewriter TTY will then be opened and held open to indicate the break signal.

It will be observed that when signals are being transmitted from the outlying point OP by op-

eration of key K, the home copy will be provided by the operation of relay B which repeats the signals to the teletypewriter TTY. The home copy thus will not be obtained from the round robin system, but rather from the local circuit at the outlying point OP.

It will be understood that any of the other stations of the round robin system may be likewise equipped with apparatus such as that shown at station CO and any outlying point may be provided with equipment similar to that shown at station OP, and thereby provide such outlying points with round robin service using only a single wire between the stations such as CO and OP.

It will be understood that the key K may be the usual sending contacts of a teletypewriter TTY₁ which is employed for sending messages to the stations of the round robin system. If desired, a single teletypewriter of well-known type may be substituted for the two teletypewriters TTY and TTY₁ shown, the single teletypewriter being used both for sending and receiving messages.

While this invention has been shown and described in certain particular embodiments merely for the purpose of illustration, it will be understood that the general principles of this invention may be applied to other and widely varied organizations without departing from the spirit of the invention and the scope of the appended claims.

What is claimed is:

1. In a teletypewriter system, the combination of a plurality of distant stations, a central office connected in a complete unidirectional loop with said distant stations to comprise a round robin system, an outlying station, a single line conductor connecting the central office with the outlying station, a teletypewriter at the outlying station, means for receiving over the conductor extending to the teletypewriter of the outlying station all messages reaching the central office, sending apparatus at the outlying station, a control relay, and means for operating said control relay for cutting said sending apparatus into said loop extending to said distant stations, said means including means for transmitting messages over said conductor through the central office to the distant stations.

2. The combination of a plurality of teletypewriter stations connected to each other in a unidirectional loop comprising a round robin system, an outlying station, a single wire line, a control relay, means for operating said control relay to connect said outlying station to the round robin system over said line, and means responsive to the operation of said control relay for receiving over said line connected to the outlying station the messages transmitted over the round robin system, transmitting apparatus at the outlying station, said latter means including means for cutting said transmitting apparatus into the round robin system for transmitting messages over said line to the teletypewriter stations of the round robin system.

3. In a teletypewriter system, the combination of a plurality of stations connected to each other in a round robin system so that signals will always be transmitted in the same direction over the system, an outlying station having transmitting apparatus and receiving apparatus, a single line conductor for connecting said outlying station with said round robin system, a control relay, means for operating said control relay for interconnecting the receiving apparatus and the stations of the round robin sys-

tem so that messages transmitted over the round robin system will be received by said receiving apparatus, means controlled by said control relay for cutting the transmitting apparatus of the outlying station into the round robin system so that messages may be transmitted from the outlying station over said line conductor to the various stations of the round robin system.

4. In a teletypewriter system, the combination of a plurality of teletypewriter stations connected to each other in a round robin system so that signals will always be transmitted in the same direction over the system, an outlying station, a control relay, and means responsive to the operation of said control means for including said outlying station in said round robin system, said means comprising a single line conductor interconnecting the outlying station with the round robin system, receiving means at the outlying station for receiving all messages transmitted over the round robin system, transmitting apparatus at the outlying station, means for cutting said transmitting apparatus at the outlying station into the round robin system so that messages may be transmitted from said outlying station over the round robin system over the single line conductor extending from the outlying station to the round robin system, and means for operating said receiving means at the outlying station in accordance with the messages transmitted from the transmitting apparatus of said outlying station.

5. In a teletypewriter system, the combination of a plurality of stations connected to each other in a round robin system so that signals will always be transmitted in the same direction over the system, a main station included in said round robin system, a control relay, an outlying station connected by a single wire conductor to the main station through the contacts of said control relay, transmitting apparatus and receiving apparatus at said outlying station, means for actuating said receiving apparatus at the outlying station in accordance with any messages transmitted over the round robin system, means for applying said transmitting apparatus to the round robin system so that messages may be transmitted over said single wire conductor to the main station and then over the round robin system, and means intercon-

necting the transmitting and receiving apparatus at the outlying station so that all messages transmitted from the outlying station may be recorded by said receiving apparatus at said outlying station.

5 6. In a teletypewriter system, the combination of a plurality of stations connected to each other in a round robin system so that signals will always be transmitted in the same direction over the system, a main station included in said round robin system, a control relay, an outlying station connected by a single wire conductor to the main station through the contacts of said control relay, transmitting apparatus and receiving apparatus at said outlying station, means for actuating said receiving apparatus at the outlying station in accordance with any messages transmitted over the round robin system, means for applying said transmitting apparatus to the round robin system so that messages may be transmitted over said single wire conductor to the main station and then over the round robin system, means interconnecting the transmitting and receiving apparatus at the outlying station so that all messages transmitted from the outlying station may be recorded by said receiving apparatus at said outlying station, and means responsive to a break signal received from any one of the stations of the round robin system for indicating at the outlying station that a break signal has been received.

30 7. In a signaling system, the combination of a plurality of telegraph stations connected to each other in a round robin system so that signals will always be transmitted in the same direction over the system, an outlying telegraph station having transmitting apparatus and receiving apparatus, a control relay for associating said outlying station with said round robin system, a single wire line connecting said outlying station to the round robin system through contacts of said control relay, means for operating said receiving apparatus in accordance with the signals transmitted over the round robin system, and means for cutting said transmitting apparatus into the round robin system for transmitting signals over said line to the telegraph stations of the round robin system.
